US0D1025938S

(12) **United States Design Patent** (10) **Patent No.:** **US D1,025,938 S**
(45) **Date of Patent:** **** May 7, 2024**

(54) **BENDABLE SCREEN**

(71) Applicant: **LG DISPLAY CO., LTD.**, Seoul (KR)

(72) Inventors: **Nakyung Han**, Paju-si (KR);
Youhong Cha, Paju-si (KR); **Jaeho Kim**, Paju-si (KR); **Dongkyu Yoon**, Paju-si (KR)

(73) Assignee: **LG DISPLAY CO., LTD.**, Seoul (KR)

(**) Term: **15 Years**

(21) Appl. No.: **29/894,354**

(22) Filed: **Jun. 8, 2023**

Related U.S. Application Data

(63) Continuation of application No. 29/797,353, filed on Jun. 30, 2021, now Pat. No. Des. 993,203.

(57) **CLAIM**

The ornamental design for a bendable screen, as shown and described.

DESCRIPTION

FIG. 1 is a front, right perspective view of the bendable screen showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines depict portions of the bendable screen that form no part of the claimed design.
